UNITED STATES PATENT OFFICE

2,044,382

MASONRY UNIT

Walter M. Dunagan, Ames, Iowa

Application October 29, 1934, Serial No. 750,559

7 Claims. (Cl. 72—66)

An object of my invention is to provide a masonry unit of simple durable and inexpensive construction.

Still a further object is to make a beam adapted to be supported at its ends and which can be inexpensively made of a special shape of building tile yet which has such a degree of inherent strength that its deflection under heavy loads is well within the limit of safety prescribed by architects and the like.

A further object is to provide an inexpensive floor slab construction which eliminates all necessity of supporting framework, yet which can be quickly fabricated on the job and thus inexpensively produced as it requires but a minimum of time for forming the masonry units and assembling them in the proper position to form a floor.

Still a further object is to provide a beam which can rigidly support a considerable load when supported at its ends, the beam being formed of short blocks of tile or the like bonded together by means of mortar in a groove extending throughout the length of the beam and in which a reinforcing rod has been embedded while the blocks are aligned on a plank or the like with the groove uppermost, after which the beam can be turned over so as to place the reinforcing rod under tension when the ends of the beam are supported.

Still another object is to provide means to prevent shearing strains between the ends of the blocks and to prevent fractures in the beam while handling it before placing it in its final position.

Still another object is to provide a floor construction which can be formed of a plurality of beams according to my invention and then be completed with a slab of plastic concrete whereby a concrete floor or sub-floor is provided.

Still a further object is to provide a method for quickly and easily precasting beams of hollow tile or the like which have sufficient strength to be formed into a floor, without the necessity of joists or other supports.

Still another object is to provide a type of construction and a method for constructing overhanging ends of the beams so that when used for a porch or the like, under supports are not required.

With these and other objects in view my invention consists in the construction, arrangement and combination of the various parts of my device, whereby the objects contemplated are attained, as hereinafter more fully set forth, point-

ed out in my claims and illustrated in the accompanying drawing, in which:

Figure 1 is a perspective view of a basement or the like illustrating the masonry units being formed according to my invention and being used to form a floor.

Figure 2 is an enlarged longitudinal view through one of the beams.

Figure 3 is a perspective view of a block or hollow tile used in forming the beams.

Figure 4 is a view of the portion of Figure 3 within the circle 4, illustrating how a channel can be formed in the lower face of the blocks when a beam supported so that it has negative bending moment is constructed.

Figure 5 is an end elevation of one of the beams during the process of forming it.

Figure 5A is a side elevation showing the formed beam turned over to the position it occupies when in use.

Figure 6 is a diagrammatic view showing a beam in side elevation and illustrating how they can be cast in an arched position.

On the accompanying drawing I have used the reference character A to indicate a block-like unit preferably formed of clay in the manner that building blocks are formed. The exact shape of the block A is immaterial, although it is preferably characterized by a channel 10 in one face thereof and channels 12 in the sides thereof. The blocks are to be cast into a beam unit such as indicated at B in Figure 1 with the channel 10 upwardly. Thereafter they are used with the channel down. The grooves 12 are preferably on the opposite side of the neutral axis or center of gravity of the unit A from the channel 10.

The blocks A are adapted to be formed into the beam B by placing a plurality of them end to end on a plank or the like 14. This can be done as illustrated in Figure 1 on the basement floor 16 of a foundation 18. The beams B are primarily designed for forming a floor by being laid side by side as shown in Figure 1. For instance if the block A is twelve inches wide and a six by twelve foot floor is to be made, twelve beams six feet long are made.

The process of making the beams B consists, after arranging the blocks A end to end on the plank 14, in partially filling the grooves or channels 12 with concrete mortar 19, then placing a reinforcing rod 20 therein and thereafter filling the channel with mortar to the level or somewhat less should construction demand of the upper faces of the blocks.

The channels 10 are preferably heavily scored as illustrated in Figure 3 to increase the bond between the concrete and the blocks to insure against longitudinal movement of the rod 20 relative to any of the blocks A.

After the channels 10 are filled and the rod 20 is in its embedded position, the grooves 12 are filled with mortar 21 in which second rods 22 of smaller diameter are embedded. After the 10 beams are thus formed or cast, they are allowed to set for a day or two, whereupon they may be handled and placed in their final position.

Without the rods 22 if the beams B were picked up off the plank 14 by their ends there would be 15 a tendency to fracture the mortar in the channel 18. That is why the rods 22 are provided and they may be of smaller diameter as their only purpose is to prevent such fracture, in addition to counteracting shearing strains between the 20 plurality of blocks A both during handling of the beam and later while carrying loads.

The beams B are turned over as in Figure 5A before they are placed on the foundation 18 whereupon the heavier reinforcing rods 20 are 25 in the tension side of the beams. This permits the beam to be supported by its ends with the tensile strength of the rod 20 counteracting any downward deflection of the beam under load. In actual tests I have found that a beam formed 30 in accordance with my method can easily support a weight of two tons without more than one-tenth of an inch deflection.

Accordingly, a plurality of these beams in forming an entire floor is entirely practical for 35 supporting heavy loads without the necessity of any supporting framework, such as joists or the like.

After the beams are placed in position on the foundation 18, screeds and other flooring may be 40 laid thereon or if the floor is to be used for heavy duty, reinforcing rods 24 can be laid transversely of the beams and a slab of plastic concrete 26 may be laid over the beams and embedding the rods 24. The rods 24 prevent fracture of the 45 concrete 26 at the joints between the successive beams. After the concrete slab is laid any floor covering desired can be laid on or secured thereon.

Instead of being used only for floors, the beams B can also be used in any other part of a structure desired. For instance, one is used at B' serving 50 as a lintel over a doorway 28. In other instances the beams B may have portions such as indicated at B'' overhanging a support such as the lintel B' to form a porch floor or other structure. To eliminate any necessity of under supports for such a floor, tension reinforcing rods 20a may be placed in the upper surface of the 55 portion B'' and in a portion of the beam B itself, as indicated in the two blocks A' and A'' in Figure 1. A channel may be provided for the reinforcing rod 20a and this is formed as shown in Figure 4 by breaking away the portion 30 of Figure 3 and filling this portion with mortar 32 in which the bar 20a is embedded. This can be 60 done either before or after the beams are placed 65 in position on the foundation.

In some instances it is desirable to preform a beam having a slight arch. This can be done as 70 shown in Figure 6 by using blocks 34 under the ends of the plank 14 when precasting the beam. On the other hand if it is desirable that the beam sag slightly, a block can be put under the plank at the center only.

Forming a floor in accordance with my method 75 makes it possible to use inexpensive tile con-

struction, yet secure all the strength required of beams used for floor construction or the like.

It will be obvious that the method of forming the beams is quite simple and takes but a minimum of time so that both for material and workmanship the expense is considerably reduced, when compared with the construction of floors as now generally done.

Changes may be made in the masonry unit without departing from the real spirit and purpose of my invention. It is my intention to cover by my claims such modified forms of construction and use of mechanical equivalents as will be reasonably included within their scope.

I claim as my invention:

1. A masonry unit comprising a plurality of masonry blocks arranged end to end, a groove in the bottom of each block, a rod extending throughout the length of the groove in said plurality of blocks and mortared therein to, through 20 tension, resist deflection of said unit when the ends thereof are supported, a second groove in each block above the center of gravity of the block and a second rod extending throughout the length of said second groove in said plurality 25 of blocks, said second rod, through tension, resisting deflection of said unit when the unit is in inverted position and the ends thereof are supported.

2. A masonry unit comprising a plurality of 30 masonry blocks arranged end to end, a groove in the bottom of each block, a rod extending throughout the length of the groove in said plurality of blocks and mortared therein, a portion of one end of said masonry unit having a groove 35 in the top of each block, a second rod extending throughout the length of said second mentioned groove in the blocks of said portion of said unit and mortared therein, said masonry unit being adapted for support on a pair of spaced supports 40 with part of said mentioned portion thereof overhanging one of said supports, said first rod, through tension, resisting downward deflection of said masonry unit between said supports and said second rod, through tension, resisting downward deflection of the over-hanging part of said 45 masonry unit.

3. A masonry unit formed of a plurality of blocks rectangular in cross section and arranged 50 end to end to form a beam, a groove in the upper face of said beam, a reinforcing rod bonded in said groove, a second groove in a vertical side of said beam located on the opposite side of the neutral plane of said beam from said first mentioned groove and a second reinforcing rod bonded in 55 said second groove.

4. A masonry unit formed of a plurality of blocks, rectangular in cross section and arranged end to end to form a beam, a groove in the upper 60 face of said beam, a reinforcing rod bonded in said groove extending throughout but terminating within the length thereof, grooves in the vertical sides of said blocks on the opposite side of the neutral plane of said beam from said first groove and reinforcing rods bonded in said second 65 mentioned grooves.

5. A masonry unit formed of a plurality of rectangular blocks arranged end to end and having each, a channel in the center of the upper face 70 thereof, mortar received therein, a bar embedded in said mortar for bonding said blocks together, said blocks having each, other channels in the sides thereof on the opposite side of the center of gravity of said blocks from said first mentioned 75

channel, mortar received in said other channels and a bar in each other channel and embedded in the mortar therein.

6. A masonry unit comprising a plurality of masonry blocks arranged end to end and divisible into a first portion and a second portion, said first portion having a groove in the bottom of each block thereof, a rod extending throughout the length of said groove and mortared therein, said second portion and a part of said first portion having a groove in the top of each block, a second rod extending through the length of said second mentioned groove and mortared therein, said first portion being adapted for support at its ends on a pair of spaced supports with said second portion overhanging one of said supports, said first rod through tension resisting downward

deflection of said masonry unit between said supports and said second rod, through tension resisting downward deflection of the overhanging part of said masonry unit.

7. A masonry unit comprising a plurality of 5 masonry blocks arranged end to end, a groove in the bottom of each block, a rod extending throughout the length of the groove in said plurality of blocks and mortared therein to, through tension, resist deflection of said unit when the ends thereof are supported, and a tension rod associated with said plurality of blocks above the center of gravity of said unit, to, through tension, resist deflection of said unit when the ends thereof are supported while the unit is in inverted position. 10 15

WALTER M. DUNAGAN.
